US00D392559S

United States Patent

[19]

Smith et al.

[11] Patent Number: Des. 392,559

[45] Date of Patent: **Mar. 24, 1998

[54] CONTAINER

[75] Inventors: **James W. Smith**, Houston, Tex.; **Mark W. Holmes**, Round Lake Beach; **Thomas E. Riley, Jr.**, Chicago, both of Ill.

[73] Assignee: **The Coca-Cola Company**, Atlanta, Ga.

[**] Term: 14 Years

[21] Appl. No.: 58,558

[22] Filed: Aug. 19, 1996

[51] LOC (6) Cl. 09-05

[52] U.S. Cl. D9/306
